US00D787533S

(12) **United States Design Patent** (10) **Patent No.:** **US D787,533 S**
Butcher et al. (45) **Date of Patent:** **** May 23, 2017**

(54) **DISPLAY SCREEN OR PORTION THEREOF
WITH GRAPHICAL USER INTERFACE**

4,457,609 A 7/1984 Tomino et al.
D295,877 S 5/1988 Wells-Papanek et al.
D303,268 S 9/1989 Yamamoto

(71) Applicant: **Apple Inc.**, Cupertino, CA (US)

(Continued)

(72) Inventors: **Gary Butcher**, San Jose, CA (US);
Alan C. Dye, San Francisco, CA (US);
Chance Graham, Campbell, CA (US);
Jonathan P. Ive, San Francisco, CA
(US)

FOREIGN PATENT DOCUMENTS

KR 30-0668662 11/2012

(73) Assignee: **Apple Inc.**, Cupertino, CA (US)

(**) Term: **15 Years**

(21) Appl. No.: **29/572,138**

(22) Filed: **Jul. 25, 2016**

OTHER PUBLICATIONS

Registered Trademark Serial No. 78157294, Seagate Technology,
filing date Aug. 23, 2002.

Goldstein & Fox P.L.L.C.

Related U.S. Application Data

(63) Continuation of application No. 29/501,164, filed on
Sep. 2, 2014, now Pat. No. Des. 762,659.

CLAIM

(51) **LOC (10) Cl. 14-04**
(52) **U.S. Cl.**

The ornamental design for a display screen or portion
thereof with graphical user interface, as shown and
described.

(58) **Field of Classification Search**
USPC D14/485; D14/491

DESCRIPTION

USPC D14/485-495
CPC G06F 3/04847; G06F 3/04842; G06Q
10/063114; H04N 1/00477; G11B 27/34
See application file for complete search history.

The file of this patent contains at least one drawing/photograph
executed in color. Copies of this patent with color
drawing(s)/photograph(s) will be provided by the Office
upon request and payment of the necessary fee.

(56) **References Cited**

The FIGURE is a front view of a display screen or portion
thereof with graphical user interface showing the claimed
design.

U.S. PATENT DOCUMENTS

The outermost broken lines in the FIGURE show a display
screen or portion thereof, and form no part of the claimed
design. The other broken lines in the FIGURE show portions
of the graphical user interface that form no part of the
claimed design.
